UNITED STATES PATENT OFFICE

ALFRED FEYENS, OF BRUSSELS, BELGIUM

ROTARY DISTRIBUTOR FOR INTERNAL COMBUSTION ENGINES

Application filed November 9, 1928, Serial No. 318,184, and in Belgium November 14, 1927.

My invention relates to a rotary distributor for internal combustion engines in which a gas-tight communication between the rotor at the single admission and exhaust orifice 5 of each engine cylinder is ensured by a movable element or packing member resiliently pressed against the body of the distributor either by the pressure in the said cylinders or by the action of springs. The rotor of the 10 distributor comprises moreover a central exhaust conduit and a concentric annular admission conduit, owing to which it is possible to obtain an even expansion of the rotor and at the same time effect the heating of 15 the admission gases and an energetic mixing of the latter, means also being provided for ensuring suitable lubrication of the contact surfaces and cooling of the bearing of the driving shaft of the rotor.

20 Merely by way of example, a construction according to the invention applied to a four cylinder engine, is described in the following with reference to the accompanying dia-

25 grammatic drawings in which:

Figure 1 is a sectional elevation of a cylinder head provided with a rotary distributor according to the present invention.

Figure 2 is a cross-section on line 2—2 of Figure 1.

30 Figure 3 is a cross-section of a modified construction.

Figure 4 is a plan of Figure 3, and

Figure 5 is a cross-section of a modified construction somewhat similar to that shown 35 in Figure 3.

As shown in Figures 1 and 2, the cylinder head *a* forming the stator, is provided with a cooling water jacket and has a bore in which is rotatably mounted the body *b* or rotor of the 40 distributor. This bore is in communication with each of the cylinders of the engine through cylindrical passages in each of which can move, with a very limited play, a packing member provided with packing rings, the 45 portion of which coming in contact with the body *b*, is correspondingly shaped. The packing member is provided with a central orifice. The rotor *b* has a central conduit *f* for the exhaust which opens at one end into the ex- 50 haust pipe *g* and is put into communication

at the correct times with each of the cylinders through suitable ports.

The annular conduit *e* surrounding the central conduit *f* is for the admission of fresh gases entering from the carburetor and passing through the orifice *d* into an end chamber *d'* of the stator *a*, the said chamber being closed by a cover *i* forming a bearing for the shaft *b'* at the opposite end of the rotor.

The movement of each element *c* constituting the packing member between the engine cylinders and the rotor may be regulated from outside to prevent excessive friction between the same and the rotor, for instance by means of oppositely arranged rods *n* slidably mounted in cylindrical partially threaded openings *o* provided on opposite sides of the cylinder head, said rods comprising cylindrical portions *t* the beveled ends *s* of which engage corresponding inclined faces of notches *s'* cut in the packing member *c*. The opposite end of the rod *n* comprises a reduced portion *t'* having a threaded end mounted with slight frictional engagement in a hollow bolt *u* where it is secured by means of a nut *v* provided on the threaded end of the rod.

The movement of the packing member *c* may thus readily be adjusted from the outside by screwing or unscrewing the hollow bolt in the threaded portion of the opening *o*. After being adjusted, the hollow bolt is secured by the set nut *w*.

In the modification illustrated in Figure 3, instead of the packing member *c*, the invention provides also for use around the orifice of the cover of the engine cylinder, of a cylindrical ring *p*, the face of which engages with the rotor. Determined by the intersection of the said ring with this rotor, the said ring is guided with a slight amount of friction in a corresponding annular groove *p'*, and subjected to the action of springs *q* provided in the bottom of the groove (Figure 3).

In the modification Figure 5, the springs may be dispensed with and the pressure in the engine cylinder may be allowed to act on the rings by making the bottom of the groove *p'* communicate with the said chamber through conduits *r*.

What I claim is:

A rotary distributor, more particularly for internal combustion engines, in which gas-tight communication between the rotor and the cylinder head constituting a stator is ensured at the orifice of each cylinder, by means of a piston-like packing member having an axial conduit for admission and exhaust, which packing member is provided with rings and pressed against the rotary distributor by the pressure in the cylinder, the said packing member being capable of a slight movement in the cylinder head and means operable from the outside wherewith to adjust the amplitude of movement of said packing member.

In witness whereof I affix my signature.

ALFRED FEYENS.
